WHEELED TOY

Aimee J. Dube, Troy, N. Y.

Application December 6, 1946, Serial No. 714,572

3 Claims. (Cl. 46—100)

1

This invention relates to toys and amusement devices and more particularly to a wheeled toy contemplated to afford considerable enjoyment to observers due to its uniqueness and novelty of operation.

An important object of the invention is to provide a toy in the form of a substantially large rolling annulus on the inner circumference of which is mounted a motivating unit for imparting rotary motion to the annulus to cause the same to roll along a surface without the application of external energy.

Another object of the invention is to provide a toy of the character stated which may simulate in fantasy a type of war machine that may be used in the future.

Still a further object of the invention is to provide a wheeled toy which may be used by children in races and other competitions.

These and various other objects and advantages of the invention will become apparent to the reader of the following description.

In the drawings:

Figure 1 is a side elevational view of the toy with a portion in section.

Figure 2 is a fragmentary vertical sectional view taken substantially on line 2—2 of Figure 1.

Figure 3 is a side elevational view, partly in section and fragmentarily showing a modified form of the invention.

Figure 4 is a section taken on line 4—4 of Figure 3.

Figure 5 is a fragmentary side elevational view, partly in section showing a third form of the invention.

Figure 6 is a section taken on line 6—6 of Figure 5.

Figure 7 is a cross sectional view fragmentarily showing still another form of the invention.

Referring to the drawings, in Figure 1, numeral 5 denotes a hollow annulus of suitable material and preferably having a thin tread covering or tire 6 of resilient material. The annulus at its inner circumferential portion has outstanding flanges 6a, 6a. Inside of the annulus is a motivating unit generally referred to by numeral 9, which consists of a frame 10 having a formation simulating a seat upon which a figure, simulating a man and denoted by numeral 11 is disposed in a sitting position, preferably holding a simulated steering wheel 12. The ends of the frame 10 have axles 13 disposed therethrough and on these are wheels 14 riding in the outer grooves 8 of the annulus flanges 6a. In the frame 10 is a conventional clock mechanism, adapted to

2

be wound by a key and stem 16, this mechanism including a driving shaft on which is a gear 17, which meshes with a ring gear 18 on one of the flanges 6a. (See Figure 2.) Depending from the side portions of the frame 10 are side walls 19 on the inner sides of which are mounted rollers 20 for riding the undersides of the flanges 6a, as in the manner shown in Figure 2.

Leg members 21, 21 extend outwardly and downwardly from the side walls 19 and declining slightly toward the rear of the motivating unit 9, as in the manner shown in Figure 1. The lower ends of these legs 21 carry wheels 22, which ride the surface on which the annulus 5 rolls.

An arm 23 suitably supported by the frame 10 has a yoke 24 at its lower end, in which a vehicle weight member 25 is rotatably mounted, this weight being concealed within the hollow annulus 5.

In the operation of this toy, the clock mechanism 15 is first wound by the key and stem 16. Upon the mechanism being released, the gear 17 will cause the motivating unit 9 to ride the inner circumference or flanges 6a of the annulus and due to the gravitating effect of the weight 25, rolling motion will be imparted to the annulus 5, while the annulus is held upright and stabilized by the ground riding wheels 22.

A modification of the invention is shown in Figure 3, wherein numeral 26 denotes an annulus having a resilient tread covering 27, this annulus having an inturned flange 28 at one side of its inner circumference and an outstanding formation 29 spaced from the flange 28 to define a shoulder 30.

Numerical 31 denotes a motivating unit which consists of a frame 32 on which is mounted a miniature swingable cannon 33. The frame 32 contains a clock mechanism generally referred to by numeral 34, this being adapted to be wound by a stem and key 35, the clock mechanism driving a gear 36, which meshes with a ring gear 37 on the flange 28.

Depending from a lug 38 on the frame 32 is a swingable yoke 39 in which a rotatable weight 40 is mounted, this being concealed within the hollow annulus 26.

Leg members 41 project outwardly and downwardly from the side walls of the frame 32 and have wheels 42 at their lower ends for riding the surface on which the annulus rolls. Brace members 43 extend downwardly to the legs 41, these brace members 43 extending from the ends of a cross shaft 44 on which is a vertical hand lever

45. If desired, a single outrigger wheel may be positioned at the rear of the annulus 26 by an arm projecting from the frame 32, in place of the wheels 42 at the sides of the annulus.

In operating the toy, the spring motor 34 is wound by rotating the key 35 and when the motor is released, rotary motion will be imparted to the gear 36, which will carry the unit 31 along the flange 23 and shoulder 30, there being rollers 46 inside of the frame 32, riding these portions of the annulus 26. The weight 40 in its gravitating effect on the annulus 26, will cause the annulus to roll along the supporting surface.

Figures 5 and 6 show another form of the invention, numeral 47 disclosing an annulus, the side portions of which can be struck out to provide openings 48, if desired. The inner circumferential portion of the annulus 47 has outstanding flanges 49, 50 which are straddled by grooved rollers 51 on the lateral flanges 52 of a frame 53, which supports a swingable toy cannon 54, within in the casing portion 55 of which is a clock mechanism adapted to be wound by a key 56, the clock mechanism drives a gear 57 on a shaft 58 supported by the frame 53, the shaft 58 having a gear 59 thereon meshing with a ring gear 60 on the annulus flange 49. Swingably supported by the frame 53 is a yoke 61 supporting a rotatable weight 62 of spherical form.

When the spring motor, contained in the casing 55 has been wound by the key 56, and released, the gear 59 in rotating will move the frame 53 longitudinally on the inner circumferential portion of the annulus 47, it being guided by the grooved wheels 51 riding the edge portions of the flanges 49, 50. The effect of the weight 62 will cause the leading portion of the annulus to depress, thus imparting rotary motion to the annulus, to the end that it rolls along the ground or other supporting surface. This form of the invention also has outrigger wheels 63 carried by arms 64 projecting outwardly and downwardly from the frame 53.

A further form of the invention is shown in Figure 7, wherein numeral 65 denotes an annulus, which may also have spaced cut-outs in the side walls thereof, these being denoted by numeral 66. The inner circumference of the annulus 65 has inturned flanges 67, 68 against which ride, internal circumferentially grooved rollers 69, 70 respectively, the roller 69 having a pulley 71 formed thereof or attached thereto, the rollers 69, 70 and the pulley 71 being rotatable on pins 72, which depend from outstanding flanges 73 of a frame 74, which forms part of a motivating unit generally referred to by numeral 75. On the frame 74 is a miniature toy cannon 76 projecting from a case 77, the latter containing a spring type motor, adapted to be wound by a key 78, this mechanism being conventional.

The conventional spring motor mechanism (not shown) has a drive shaft 79 on which is a small pulley 80 and trained over this pulley 80 and the pulley 71 is an endless element 81. This endless element 81 may extend to operate two such wheels as the wheels 69, in which instance there would be a second pulley 71.

Depending from the frame 74 is a lug 82 to which is secured a yoke 83 in which a rotatable ball-shaped weight 84 is mounted. This form of the invention also has outrigger arms 85 and supporting stabilizing wheels 86.

In the operation of this form of the invention, the spring motor in the case 77 is wound by the key 78 and upon release of the spring mo-

tor, the shaft 79 is driven, this in turn, by way of the endless element 81, drives the pulley or pulleys 71 and the grooved wheels 69, which results in the movement of the unit 75 along the flanges 67, 68, the weight 84 effecting, by gravitation, a rotary motion of the annulus 65.

It is to be understood that the cross sectional shape or dimension of the annulus is immaterial and that the shape and material of the weight 84 or the corresponding weights in the other modifications are immaterial.

Various figures or war machine simulations may be used on each of the motivating units.

The device is not only thrilling and amusing in operation to children, but as well as for adults.

While the foregoing description sets forth the invention in specific terms, it is to be understood that numerous changes in the shape, size and materials may be resorted to without departing from the spirit and scope of the invention as claimed hereinafter.

Having described the invention, what is claimed as new is:

1. A toy comprising an annulus and a traveling unit at the inner circumference of the annulus for imparting rotary motion to the annulus, said annulus being provided with spaced coplanar flanges at its inner circumference, said unit being provided with rollers for riding said flanges, said rollers being circumferentially grooved to receive the edge portions of said flanges.

2. A toy comprising an annulus and a traveling unit at the inner circumference of the annulus for imparting rotary motion to the annulus, said annulus being provided with spaced coplanar flanges at its inner circumference, said unit being provided with rollers for riding said flanges, said rollers being circumferentially grooved to receive the edge portions of said flanges, and an outrigger wheel connected to the traveling unit for stabilizing the annulus while in motion.

3. A toy comprising an annulus and a traveling unit at the inner circumference of the annulus for imparting rotary motion to the annulus, said annulus being provided with spaced coplanar flanges at its inner circumference, said unit being provided with grooved wheels for riding the edge portions of said flanges, certain of said grooved rollers being provided with pulleys operating in unison therewith, a spring wound motor on the unit, a pulley driven by the spring wound motor and an endless element trained around said pulleys whereby power is delivered from the motor to the grooved rollers for causing the unit to travel on the inner circumference of the annulus.

AIMEE J. DUBE.
